HOLLOW HAIR CURLER

Noel O. Stimson, Los Angeles, Calif.

Application May 17, 1948, Serial No. 27,417

2 Claims. (Cl. 132—42)

1

This invention relates to an improved hollow hair curler.

It is an object of this invention to provide a hollow hair curler of the kind to be more particularly described hereinafter to permit the free movement of air within the curl to be effected whereby the wet hair may be rapidly dried.

Another object of this invention is to provide a hair curler of this kind which may be removed from hair in a semi-dry condition without disturbing the design of the curl and permits pinning of the curl at this point by hair pins, since the one part of the curler becomes a tool or former to aid in the pinning of the curl in a perfect curled position, and upon removal of the second part, the hair can be left in the curled condition and allowed to dry with or without specifically directed warm air or the use of a drier.

Still another object of this invention is to provide a curler of this kind having elongated perforations running lengthwise of the body to present a flat or straight line along the curler, with this type of perforation, the hair is not permitted to fit down in the open spaces as would be permitted with round openings; therefore the hair is held from becoming locked or fitted in the openings and will slide and come free of the curler without any markings on the wrapped curl.

A further object is to provide a curler highly desirable and advantageous in the process of permanent waving, as in a cold wave, since it permits the inner drying or curing to take place from within the curler, as well as from the outside and permits inner saturation of the curl when fixing solutions are employed.

A still further object of this invention is to provide a curler which is advantageous and desirable for permanent waving when chemical heat pads are employed as the curler is hollow and perforated and permits the application of inner heating of the curl by chemical or mechanical means.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a side elevation of a hair curler constructed according to an embodiment of my invention.

2

Figure 2 is a vertical section of the curler shown in Figure 1.

Figure 3 is a transverse section taken on the line 3—3 of Figure 1.

Figure 4 is a transverse section taken on the line 4—4 of Figure 1.

Figure 5 is a side elevation of a modified form of this invention.

Figure 6 is a transverse section taken on the line 6—6 of Figure 5.

Figure 7 is a side elevation of the lower member of another modified form.

Referring to the drawing, the numeral 10 designates generally a hair curler constructed according to an embodiment of this invention which is formed of metal, plastic or other suitable material for providing a hollow body 11 open at both ends thereof. The hollow body 11 is formed of an upper section 12 and a lower section 14 which are slidably connected together at one end thereof. Each of the sections 12 and 14 are substantially frusto-conical in configuration and formed with thin walls. The narrow end as 15 of the lower body section 14 is substantially cylindrical in shape and the lower end 16 of the upper section 12 is also cylindrical for telescoping engagement over the cylindrical end 15 of the lower section 14.

The side walls of the body 11 are formed with elongated openings as 17 therein which are disposed in substantial axial alignment along the length thereof. The openings 17 are elongated in the direction of the length of the curler 10 to provide for the admission of drying air through the walls whereby hair which is curled on the device may be exposed to drying air interiorly of the curl formed thereon. The openings 17 are formed in the walls of the body 11 by striking vanes 18 inwardly. The vanes in this manner are formed integral with the walls of the device and are adapted to be struck inwardly to provide L-shaped vanes of this kind which have an axial arm 19 and a transverse arm 20. The transverse arm 20 connects the vertical arm 19 of the vane to the wall and the end of the vane closest to the end of the body 11 is left free. In this manner the air is permitted to enter the ends of the body 11 and to be deflected inwardly and radially of the curler 10 and of the curl of hair disposed thereon.

As noted above the cylindrical section of the lower body portion 14 is adapted to be telescoped into the cylindrical section of the upper section 12. For holding the two body portions 12 and 14 against rotation relative to each other, I have

provided guide means which are formed integral with the cylindrical portions of the bodies for interengagement between the cylindrical sections. The cylindrical section 15 of the lower body portion 14 is formed with outwardly bent guide beads 21 which terminate at the upper or free end of the cylindrical section. Guide beads 22 are bent from the lower end of the cylindrical section 16 of the upper portion 12 and the beads 21 are adapted to be slidably engaged within the grooves or channels 22. In this manner a sliding engagement of the two body sections is obtained and the body sections when engaged are held against rotation relative to each other.

For securing the two body sections 12 and 14 together I have provided a resilient flexible connecting member 24. The connecting member 24 may be made of rubber or plastic or other suitable flexible material and is fixed at one end to the divergent end of one of the body sections as the body section 12. A radially extending arm as 25 is formed integral with the divergent open end of the body section 12. The arm 25 may lie substantially flush with the plane of the open end of the curler or may be spaced inwardly therefrom. An opening 26 is provided in the arm 25 and the end of the band 24 is fixed into the opening 26.

A spring clip as 27 is carried by the other end of the resilient connecting member 24. The spring clip 27 is formed of a short length of metal which is bent into opposed U-shaped members each having a pair of substantially parallel arms 28 connected together by a common bight portion 29. The free ends of the arms 28 are disposed in divergent relation one to the other to provide an entrance channel into the clip 27. The flexible member 24 is fixed in an opening in the bight 29 for securing the clip 27 thereto. The length of the resilient connecting member 24 is substantially the same as the length of the full body 11 so that when a curl of hair is disposed about the body 11 the connecting member 24 will be disposed outwardly of the curl and will be tensioned when the clip 27 is engaged with the divergent end of the other body section 14. As one of the U-shaped members is engaged as a clip, the opposite member is disposed as a handle or finger grip for the clip 27.

In the use and operation of this curler 10 the two body sections 12 and 14 are slidably connected together by engaging the cylindrical sections 15 and 16 together and slidably engaging the bead 21 into the guide channel 22. The hair to be curled is wrapped about the body 11 and the flexible member 24 is stretched over the curl and the clip 27 is engaged with the free divergent end of the lower body section 14. In this manner the hair is securely mounted on the curler 10 and the two sections 12 and 14 of the curler are secured together.

In Figures 5 and 6 there is disclosed a modified form of curler 30 formed of body sections 31 and 32 which are formed in substantially the same manner as the body sections 12 and 14 described above. In the curler 30 the cylindrical sections 34 and 35 are slidably connected together and no means is provided for restraining the rotation of the two body sections one relative to the other. A connecting member 36 is fixed at one end to one of the body sections as 31 in the same man-

ner as described for the body section 12 and the connecting member 24. The same type of clip as 27 may be used on the flexible member 36 for securing the body sections 31 and 32 together. 5 In the preferred form of the modified body section the connecting cylindrical sections 34 and 35 may be slightly frusto-conical to provide for a secure connection therebetween, the frusto-conical formation of the sections 34 and 35 being 10 opposed or opposite from the formation of the main body section to which the cylinder is attached. In other words, the convergent end of the section 34 would be connected to the convergent end of the body section 31. The convergency of the connecting sections 34 and 35 would be very small so that the two sections 34 and 35 may be slidably connected together upon the exertion of suitable force for sliding the divergent end of the section 35 into the divergent 20 end of the section 34.

The size of the openings in the walls of the curlers may be varied within the scope of this invention and are preferably long and narrow as shown in Figure 7 of the drawings. In Figure 7, 25 the openings 17a of the curler 10a are relatively narrow and certain of the axially related openings are offset from adjacent openings. It will be understood that the size, number, and relative arrangement of the openings 17a may be altered 30 as found most desirable. It is contemplated also that some curlers will be made without vanes, as vanes 19, and others with a smaller number of vanes.

I claim:

- 35 1. An improved hair curler comprising a pair of open ended hollow tubular members, means slidably connecting said members together in axial alignment, elongated instruck tongues on said members along the length thereof defining perforated walls and axially disposed guide vanes 40 therein, and a resilient connecting member engaging the remote ends of said tubular members for securing said members together and for securing a curl of hair thereon.
- 45 2. An improved hair curler comprising a pair of open ended hollow tubular members, means slidably connecting said members together in axial alignment, elongated instruck tongues on said members along the length thereof defining 50 perforated walls and axially disposed guide vanes therein, a resilient connecting member engaging the remote ends of said tubular members for securing said members together and for securing a curl of hair thereon, and correlated interengaging 55 guide means on the adjacent ends of said tubular members restraining said tubular members against relative rotation one to the other.

NOEL O. STIMSON.
